Certificate

Patented: November 1, 1994

Patent No. Des. 352,039

On petition requesting issuance of a certificate for correction of inventorship pursuant to 35 U.S.C. § 256, it has been found that the above-identified patent, through error and without any deceptive intent, improperly sets forth the inventorship.

Accordingly, it is hereby certified that the correct inventorship of this patent is: Philip Yurkonis, Alison Armstrong, Paul S. Montgomery and Herbert H. F. Pfeifer.

Signed and Sealed this Twenty-second Day of April, 1997.

THEODORE SHOOMAN
Supervisory Primary Examiner
Art Unit 2902
